DRAFTING MECHANISM FOR TEXTILE FIBERS

Joseph Noguera, Prestwich, Manchester, England,
assignor to Casablancas High Draft Company
Limited, Manchester, England, a British company

Application December 15, 1942, Serial No. 469,101
In Great Britain December 1, 1941

2 Claims.

(Cl. 19—130)

This invention relates to drafting mechanisms for textile fibers of the type in which the fiber passes between each of three or more pairs of rollers, the intermediate pair or pairs of rollers acting as drawing rollers with respect to the preceding pair and as retaining rollers with respect to the succeeding pair.

In a normal mechanism of this type, the superposed axes of the pairs of rollers lie in parallel planes, while the nips of the pairs of rollers are in substantial alignment. With this type of mechanism the amount of draft which can be satisfactorily performed between any two pairs of rollers is small. In machines where comparatively thick masses or strands of fiber are being drawn, such as, for example, in the draw-frames and speed-frames in cotton spinning, the difficulty is increased because, owing to the considerable interfiber adhesion in the thick strand, the distance between two consecutive pairs of rollers has to be substantially greater than the length of the longest fibers. The result is that between the two pairs of rollers, that is, in the space where the drafting takes place, the strand is almost entirely uncontrolled, and is therefore apt to yield to the pull of the drafting rollers in a haphazard and irregular manner. The nip formed by each pair of rollers is also unsatisfactory when dealing with a large bulk of fiber because whilst the centre or core of the strand is squeezed or trapped hard in between the two rollers, numerous fibers are left on either side of the almond-shaped cross-section of the strand which are not held sufficiently or are not held at all. This applies to each pair of rollers both in connection with their retaining action and with their drawing action.

The invention provides a drafting mechanism in which the rollers are disposed in such manner that the drawing action and/or the retaining action of the rollers are much improved, especially in the drafting of very thick strands of fiber.

According to the invention, in a drafting mechanism of the type described, the rollers are arranged in such manner that the plane containing the axes of one pair of rollers is at right angles to the plane containing the axes of the preceding and succeeding pairs respectively, whereby the strand on leaving each of two consecutive pairs of rollers is pulled round over about a quarter of the surface of one of the rollers of each pair, after which it passes straight into the nip of the succeeding pair.

In the accompanying diagrammatic drawing:

Figure 1 illustrates a drafting mechanism according to the invention consisting of three pairs of rollers.

Figure 2 also illustrates a drafting mechanism consisting of three pairs of rollers but differently arranged.

Figure 3 illustrates a drafting mechanism consisting of five pairs of rollers.

Thus, in its simplest embodiment, as illustrated in Figure 1 of the accompanying drawing, a drafting mechanism according to the present invention consists of three pairs of rollers 1, 1a, 2, 2a and 3, 3a. The strand 4 on leaving the pair of rollers 1, 1a is pressed against about a quarter of the surface of the roller 1a before passing straight into the nip of the pair of rollers 2, 2a. Similarly, the strand on leaving the pair of rollers 2, 2a is pressed against about a quarter of the surface of the roller 2a before passing straight into the nip of the pair of rollers 3, 3a.

The three pairs of rollers 1, 1a, 2, 2a and 3, 3a may also be arranged as shown in Figure 2 of the accompanying drawing, which is self-explanatory.

A drafting mechanism according to the present invention consisting of five pairs of rollers is illustrated in Figure 3 of the accompanying drawing.

30 In these arrangements according to the invention the strand of fiber is pressed against one of the rollers of each of at least two consecutive pairs for about 90° of its surface, and a very substantial measure of effective, yet yielding, fiber control is afforded. The drawing action of the intermediate pairs of rollers is made more efficient because as the drawn fibers are subsequently pulled around one of the rollers, they tighten amongst themselves and this assists in compelling forward the whole strand.

What I claim and desire to secure by Letters Patent of the United States is:

1. A drafting mechanism for textile fibers of the type in which the strand of fibers passes between each of three pairs of rollers, the intermediate pair of rollers acting as drawing rollers with respect to the preceding pair and as retaining rollers with respect to the succeeding pair, in which the rollers are arranged in such manner that the plane containing the axes of the intermediate pair of rollers is at right angles to the planes containing the axes of the preceding and succeeding pairs respectively, whereby the strand on leaving each of the first two pairs of rollers is pulled round over about a quarter of the

surface of one of the rollers of each pair, after which it passes straight into the nip of the succeeding pair.

2. A drafting mechanism for textile fibers of the type in which the strand of fibers passes between at least three pairs of rollers, the intermediate pairs of rollers acting as drawing rollers with respect to the preceding pair and as retaining rollers with respect to the succeeding pair, in which the rollers are arranged in such manner that the plane containing the axes of any pair

of rollers except the first and last pairs is at right angles to the plane containing the axes of the immediately preceding and succeeding pairs respectively, whereby the strand on leaving each of two consecutive pairs of rollers but not including the last pair is pulled round over about a quarter of the surface of one of the rollers of each pair, after which it passes straight into the nip of the succeeding pair.

JOSEPH NOGUERA.
